[57] CLAIM

The ornamental design for a connecting element for strut members or the like, substantially as shown.

DESCRIPTION

FIG. 1 is a front elevational view of a connecting element for strut members or the like showing my new design;

FIG. 2 is a rear elevational view thereof;

FIG. 3 is a top plan view thereof;

FIG. 4 is a bottom plan view thereof;

FIG. 5 is a left side elevational view thereof; and,

FIG. 6 is a right side elevational view thereof.
